UNITED STATES PATENT OFFICE.

OTTO Y. SCHNERING, OF CHICAGO, ILLINOIS.

DESIGN FOR A COMBINED VENDING JAR AND BASE.

Application filed June 14, 1928. Serial No. 27,128. Term of patent 14 years.

To all whom it may concern:

Be it known that I, OTTO Y. SCHNERING, a citizen of the United States, residing at Chicago, Illinois, have invented a new, original, and ornamental Design for a Combined Vending Jar and Base, of which the following is a specification, reference being had to the accompanying drawing, forming part thereof.

The figure is a perspective view showing my new and ornamental design.

I claim:—

The ornamental design for a combined vending jar and base substantially as shown.

OTTO Y. SCHNERING.
